UNITED STATES PATENT OFFICE.

WILLIAM H. MOUNT, OF SUMMIT, NEW JERSEY.

SHIPPING AND DISPLAY BOX.

Original application filed October 10, 1922, Serial No. 593,593. Divided and this application filed November 24, 1925. Serial No. 71060.

The invention relates to novel, simple and economical shipping and display boxes and the like, which can be shipped in a knocked down state and assembled by the user with unskilled labor. The box can be used time and again and can be made into a display cabinet if desired.

This application is a division of my co-pending application for shipping and display box, Ser. No. 593,593, filed October 10, 1922.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate several embodiments of the invention, but to which my invention is not to be confined, and together with the description, serve to explain the principles of the invention.

30 Of the drawings:—

Fig. 1 is a fragmentary perspective view of the simplest form of my invention;

Fig. 2 is a detail horizontal section on line 2—2 of Fig. 1;

Fig. 3 is a fragmentary perspective view, similar to Fig. 1, with the addition of one form of sealing means;

Fig. 4 is a detail fragmentary horizontal section showing a modified form of sealing means;

Fig. 5 is a detail fragmentary horizontal section similar to Fig. 2;

Fig. 6 is a section on line 6—6 of Fig. 5;

Fig. 7 is a section on line 7—7 of Fig. 5.

45 My invention relates to shipping and display boxes and the like and more particularly to one which can be manufactured by the simplest machines and at small cost. It further relates to such a box which can be knocked down to take up the minimum space.

Besides the low cost of manufacture, the box has many other advantages among which are the following:

It can be assembled by the user with the aid of unskilled labor; no nails, screws, or other

similar fastenings are employed; it can be used over and over again and stored in a knocked down condition when not in use; it will not only protect the article shipped in the box, but it can serve as a display cabinet 66 to display the article, which is normally packed within it, or as a stand for said article; when a sealing device is employed, a glance at the box will show whether or not its contents have been tampered with; there 65 is an appreciable saving in material in the length of its sides and ends as compared with ordinary box construction of the same capacity; if the box is to be stained and varnished this can be done before the box is assembled, by dipping, which is the cheapest 70 form of finishing; there are no nail holes to putty when staining and varnishing; there is no gluing or clamping of the box, the box is as strong as one formed by nailing, without 75 the disadvantage of having to break or mar the box to unpack it; by making the sides and ends of boards of different widths, a box can be built of any height and still use the same bottom and cover which permits less stock to 80 be carried.

In my box the sides, ends, top and bottom all have cooperating engaging surfaces which serve to hold the different members of the box together without the aid of nails or 85 screws or similar fastening means.

I have shown in Figs. 1 and 2, a knock-down shipping and display box 1, having the removable ends 2 and 3 and removable sides 4 and 5. The box is also provided with a 90 removable cover 6 and a removable bottom 7. The metal reenforcing members 20, 20 of the ends 2 and 3 are provided with tongues 8, 8 which fit into cooperating grooves 9, 9 in the metal reenforcing members 18, 18 of the 95 sides 4 and 5. The metal reenforcing members 18, 18 are also provided with interlocking tongues 10, 10 which fit into cooperating grooves 11, 11 in the metal reenforcing members 20, 20 of the ends 2 and 3, so that each 100 of the ends and sides have both a tongue and groove. The metal reenforcing members 18, 18 and 20, 20 are also provided with grooves 12, 12, the arrangement being such that a pair of these grooves forms a single groove 105 for the reception of one of the key pegs 13, one key peg being in each corner of the box. The sides 4 and 5 and the ends 2 and 3, including their respective reenforcing metal members, are provided with horizontal 110

grooves 14, 14 for the reception of the tongue 15 mounted on the bottom 7 (see Fig. 5). This tongue 15 extends out on all sides of the bottom 7, the sides 4 and 5, with their reenforcing members 18, 18 and the ends 2 and 3 with their reenforcing members 20, 20 are also provided with a similar groove 16 within which fits the tongue 17 of the cover 6.

By forming the major portions of the sides 10 and ends of wood, or similar material, which may be relatively thin, and using the metal reenforcing members 18 and 20, I obtain a strong box and one that is strengthened at the corners where the greatest strains occur.

15 In addition to strengthening the ends of the box by metal reenforcing members, I secure together the pair of reenforcing members, on each side or end, so that any strain or blow on one reenforcing member will be transmitted to the adjacent reenforcing member.

20 I secure the wood or other weak member of the sides and ends to their respective metal reenforcing member by providing registering holes 22, 22 in the weak or wood members, 25 and corresponding holes 23, 23 in the metal members or other strong portion of the sides and ends (Fig. 2), and thread the end 24 of the tieing wire 25 through these registering holes and then wrap the end 24 around 30 the securing wire 25. The other end of the tieing wire 25 is passed through corresponding holes 22, 23 in the adjacent side member 18, or end member 20, as the case may be, to secure the reenforcing metal members to their 35 respective wood sides or ends. This avoids the use of nails or screws and transmits any strains or stresses on one end of the box to the other end by means of the tieing wire 25.

40 In assembling the box the sides 4 and 5 are brought into cooperative relation with the tongue 15 of the bottom 7 so that this tongue will be located within the groove 14 in the metal and wood portions of the sides 4 and 5. One of the ends, preferably 2, is then 45 brought into cooperative relation so that its tongue and grooves in its metal reenforcing member 20, 20 cooperate with the grooves on the metal reenforcing members 18, 18 on the sides 4 and 5. Two key pegs 13, 13 are 50 then slipped into the grooves 12, 12 formed partly in the end 2 and sides 4 and 5. The cover 6 is then brought into cooperative position so that its tongue 17 can slide in the 55 grooves 16, 16 of the sides 4 and 5; that portion of the tongue 17 on the end of the cover 6 is received in the portion of the groove 16 located in the end 2. The end 3 is then brought up into cooperative relation with the sides 4 and 5, the cover 6 and bottom 7, which 60 will then close the box. In this position the tongue 17 of the cover is received in the groove 16 in the ends 2 and 3, and the tongue 15 of the bottom 7 is received in the groove 14 in the ends 2 and 3. In securing the parts in 65 this position, two more key pegs 13, 13 are

dropped or forced into the grooves 12, 12, formed partly in the reenforcing members 18, 18 of the sides 4 and 5 and the end 3. The box is then ready to be shipped without any nailing or other fastening means being employed. 70

I also, but not necessarily, use one or more binding wires 27, 27 extending around the sides of the box and engaging with the tieing wires 25, 25, preferably by being wound 75 around said wires, as shown in Fig. 1.

The consignee can readily unpack the box, without defacing it, and with a minimum amount of trouble, by simply pressing, with a blunt tool, for example, the two key pegs 80 13, 13 shown in the right of Fig. 1, which will permit the end 3 to be removed from the other part of the box. The cover 6 can then be pulled out so that the contents of the box are exposed. By removing the other two key pegs 85 13, 13, and the binding wires 27, 27, if they be employed, the entire box can be knocked down and stored away in a minimum space, until such time as it may be desired to again 90 use it, when it can be assembled in the manner previously described at length. It is to be noted that it is not necessary to deface the box to open it, and that it can be used over and over again.

95 In some cases I may use a seal, of any suitable construction, in connection with the box, so as to show at a glance whether or not the contents of the box have been tampered with during shipment. Any suitable form of sealing means may be employed, such as for example as shown in my patent application Ser. No. 593,593, or any other form of seal may be employed. It is to be understood, of course, that my invention is not limited to the particular form of seal which 100 may be used, and that the box may be used without any seal whatever.

105 I have shown one form of sealing means in Fig. 3 in which a sealing wire 35 is passed around the ends of the box and over two of 110 the key pegs 13, 13 (only one being shown in Fig. 3), the ends of the wire being secured by the seal 36, which is adapted to be received in a recess 37 in the side 4.

115 I have shown another form of seal in Fig. 4 in which the sealing wire 38 passes through holes 39 and 40 in the metal reenforcing members 18 and 20 at one end of the box, and through a hole 41 in the key peg 13, it being understood that this arrangement is duplicated at each end of the box so that the sealing wire 38 passes through all four of the key pegs 13, 13 and its ends are sealed by any suitable form of seal, as for example, 36. Or, 120 the sealing wire 38 may only pass through one key peg 13 and have its ends secured by any suitable form of seal, such as for example the seal 36.

125 While I have shown these particular forms of sealing means, it is, of course, to be under- 130

stood that any form of sealing means may be employed.

The invention in its broader aspects is not limited to the specific boxes or similar members shown and described, but departures may be made therefrom within the scope of the accompanying claims without departing from the principles of the invention and without sacrificing its chief advantages.

10 What I claim is:—

1. A new article of manufacture comprising a side or end of a knock-down box having metallic strengthening members at each end and a relatively weak intermediate member, the strengthening members being provided with grooved interlocking means to detachably engage and hold a complementary member and means passing transversely through the strengthening member and the intermediate member to fasten said members together and extending longitudinally thereof to connect the strengthening members.

2. A new article of manufacture comprising a side or end of a knock-down box having metallic strengthening members at each end and a relatively weak intermediate member, the strengthening members being provided with grooved interlocking means to detachably engage and hold a complementary member and means passing transversely through the strengthening member and the intermediate member to detachably fasten said members together and extending longitudinally thereof to connect the strengthening members.

3. A new article of manufacture comprising a side or end of a knock-down box having metallic strengthening members at each end and a relatively weak intermediate member, the strengthening members being provided with grooved interlocking means to detachably engage and hold a complementary member and means passing transversely through the strengthening member and the intermediate member to fasten said members together and extending longitudinally thereof to connect the strengthening members.

diate member a plurality of times to detachably fasten said members together and extending longitudinally thereof to connect the strengthening members. 45

4. A new article of manufacture comprising a side or end of a knock-down box having metallic strengthening members at each end and a relatively weak intermediate member and means passing transversely through the strengthening member a plurality of times to fasten said members together and extending longitudinally thereof to connect the strengthening members. 50 55

5. A new article of manufacture comprising a knock-down shipping and display box having sides and ends of wood, each wooden side and end being provided with metal reinforcing interlocking members detachably fastened thereto, means to connect each reinforcing member on each side and end with the re-enforcing member on the same side or end, so as to transmit strains from one re-enforcing member to the other, a top, a bottom and means attached to said connecting means to further bind the box together. 60 65

6. A new article of manufacture comprising a knock-down shipping and display box having sides and ends of wood, each wooden side and end being provided with metal reinforcing interlocking members detachably fastened thereto, wires to connect each re-enforcing member on each side and end with the re-enforcing member on the same side or end, so as to transmit strains from one re-enforcing member to the other, and at the same time secure the metal re-enforcing members to their respective wood members, a top, a bottom and other wires connected to said first-mentioned wires and extending transversely thereof to further bind the box together. 70 75 80 85

In testimony whereof, I have signed my name to this specification.

WILLIAM H. MOUNT.
